UNITED STATES PATENT OFFICE

ROBERT L. WEISNER, OF DURHAM, NORTH CAROLINA, ASSIGNOR, BY DIRECT AND MESNE ASSIGNMENTS, OF ONE-HALF TO THE AMERICAN TOBACCO COMPANY, OF NEW YORK, N. Y., A CORPORATION OF NEW JERSEY, AND ONE-HALF TO COMAS CIGARETTE MACHINE COMPANY, OF SALEM, VIRGINIA, A CORPORATION OF VIRGINIA

TOBACCO STEMMING MACHINE

Application filed July 7, 1930. Serial No. 466,234.

My invention relates to tobacco stemming machines and more particularly to that type of stemming machine disclosed in my application, Serial No. 376,915, filed July 9, 1929. A 5 principal object of the invention is to provide a tobacco stemming machine of the type having an endless belt with means for subjecting each leaf to a plurality of successive stripping operations to more quickly and 10 efficiently strip the lamina of the leaf from its stem.

Another object of the invention is to provide means for cutting the stem of the leaf adjacent its tip end so that this portion of the 15 stem which is suitable for use will not be discarded with the remainder of the stem.

A primary feature of the invention consists in providing the stemming machine with an endless belt having a set of devices for stripping the lamina of the leaf from its stem, the 20 devices being successively operable so that each strips only a portion of the lamina.

Another feature of the invention consists in providing the stemming machine with an 25 endless belt having a plurality of devices for stripping the lamina of the leaf from its stem, each of said devices having a portion movable into and out of cooperation with the leaf whereby said devices are adapted to strip suc- 30 cessive portions of the lamina from the stem.

A further feature of the invention consists in mounting a plurality of sets of the stripping devices on the endless belt so that when 35 one set of the devices has finished its stripping operation on a leaf or a plurality of leaves the next set of devices is brought into operative association with another leaf or group of leaves.

A still further feature of the invention consists in providing a pair of endless belts arranged in superposed relation, each of said 40 belts being provided with a set of devices adapted to cooperate with the corresponding devices of the set on the other belt, the devices of each set being arranged in tandem and being successively operable to strip portions of the lamina from the stem.

A still further feature of the invention consists in providing one of the stripping devices

with means for cutting the stem of the leaf adjacent its tip end.

Other and more specific features of the invention residing in advantageous forms, combinations and relations of parts will herein-after appear and be pointed out in the claims. 55

In the drawings illustrating a preferred embodiment of the invention:

Figure 1 is a side elevational view of the superposed endless belts with their cooperat- 60 ing sets of devices, parts of the mechanism of the upper belt being broken away.

Figure 2 is a detailed sectional view taken on line 2—2, Figure 1.

Figure 3 is a sectional view taken on line 65 3—3, Figure 2.

Figures 4 and 5 are detailed sectional views taken on lines 4—4, 5—5, Figure 3, respectively.

Figure 6 is a side elevational view of the 70 stripping devices provided with the cutting means.

Figure 7 is a plan view of the device illus- 75 trated in Figure 6.

Figure 8 is an end view of this device in operative position.

Figure 9 is a similar view of the device in inoperative position.

Figure 10 is an enlarged sectional view taken on line 10—10, Figure 6. 80

Figure 11 is a detailed elevational view of the stripping plate of the device illustrated in Figure 6.

Figure 12 is a detailed elevational view of the cutter member of the device illustrated in 85 Figure 6.

Figure 13 is an enlarged sectional view taken on line 13—13, Figure 12.

Figure 14 is a perspective view of another 90 of the stripping devices.

Figure 15 is a perspective view of one of the members for operating one of the strippers.

Figures 16, 17 and 18 are diagrammatic views illustrating different stripping positions of a portion of the mechanism. 95

In the stemming machine illustrated in my application heretofore referred to there is shown two stripping devices each comprising a pair of superposed endless belts. One of these stripping devices is adapted to strip 100

the lamina from adjacent the butt end of the leaf while the other stripping device is adapted to strip the remainder of the lamina. The present invention relates to improvements in the second or main stripping device illustrated in that application. As the description of the present invention proceeds it will be appreciated however that it is not limited in its application to a machine of the exact type illustrated in my pending application heretofore referred to and that instead of being employed in conjunction with means for stripping the lamina adjacent the butt of the leaf it may in itself be used to perform the entire stripping operation.

In general the present invention comprises two endless belts upon each of which is mounted a plurality of sets of stripping devices, the sets being arranged so that the devices of each set on one belt respectively cooperate with the corresponding devices of each set on the other belt. Although any number of sets may be employed and although any number of devices may comprise a set I have found from repeated tests that best results can be obtained by employing three sets on each belt and three devices to a set. Associated with each of the belts is mechanism for successively moving the devices of each set into operative and inoperative positions whereby although all of the devices of one set entirely strip the lamina from one or a group of leaves, each device of each set only strips a portion of the lamina from the leaf. By subjecting each leaf or each group of leaves to a plurality of successive stripping operations the leaf or leaves are more efficiently and more quickly stripped as the lamina is prevented from packing or bunching in front of the strippers whereby the latter would be rendered more or less inoperative or would result in the stem of the leaf being broken and inadvertently carried away with the lamina. Since the portion of the stem adjacent the tip end of the leaf is comparatively small and is therefore suitable for use and need not be discarded as must the other part of the stem the stripping device of each set on one of the belts last to operate on the leaf is provided with mechanism for severing or cutting the stem adjacent the tip end of the leaf.

Referring more particularly to the drawings 1 and 2 represent the upper and lower endless belts which are arranged in superposed relation. Each of the belts may advantageously be formed of a pair of sprocket chains 3 preferably connected by a plurality of flat bars or strips 4. The sprocket chains of each belt cooperate with and are supported by pairs of sprocket wheels 5 and 6, the wheels 5 being mounted upon a shaft 7 and the wheels 6 being mounted upon a shaft 8. Motion may be imparted to the belts by driving

either shaft of both belts by any suitable means (not shown).

Mounted upon the outer side of each of the endless belts is a plurality of sets of stripping devices, the devices of one set being designated by A¹, A² and A³, the devices of another set being designated by B¹, B² and B³ while the devices of the other set are designated by C¹, C² and C³. As may be clearly seen from the drawings the devices of each set are arranged in tandem and the sets of the devices are so spaced that as soon as one set has completed its stripping operation the other set is in position to begin its stripping operation.

Each device of each set comprises a base plate 9 which is rigidly secured to an adjacent strip or bar 4 of the associated belt by means of rivets 10 and a member 11 pivotally connected to the base plate 9 by pins 12 which extend through lugs 13 projecting upwardly from the base plate and preferably formed integrally therewith. The pivoted member 11 is formed with a plate portion 14 having a serrated edge forming a plurality of teeth 15, the plate being preferably detachably mounted by screws 16 so that it may be readily renewed or replaced should it become unfit for use. Depending from each stripping device and rigidly secured to the pivoted member 11 thereof is an angularly shaped bracket or lug 17 adapted to cooperate with mechanism for actuating the pivoted member 11 to cause the latter to assume an operative position and to permit it to assume an inoperative one. The strips or bars 4 of the endless chain at the rear of each stripping device and the strips or bars to which the base plates 9 of the stripping devices are secured as well as the base plates themselves are suitably recessed or apertured to permit of free movement of the brackets or lugs 17 of the stripping devices.

The mechanism for actuating the stripping devices comprises a plurality of bars respectively designated 18, 19 and 20 which extend longitudinally of the belt and are arranged in spaced relation transversely thereof. As may be most clearly seen from Figure 3 the bar 18 extends from adjacent the inner or intake end of the belt for a relatively short distance, bar 19 extends from intermediate the ends of bar 18 to a point beyond the outer end of the latter while bar 20 extends from a point intermediate the ends of bar 19 and terminates adjacent the outer or outlet end of the belt. The brackets 17 of the stripping device of each set are arranged in staggered relation with respect to each other so that the bracket 17 of the first stripping device of each set cooperates with bar 18 while the bracket of the second stripping device cooperates with bar 19 and the bracket of the third stripping device cooperates with bar 20.

The actuating bars may be supported in any convenient manner between the upper and lower sections of the associated belt as by a member 21 which may be suitably journaled upon the sprocket shafts 7 and 8 of the belt. As it is sometimes necessary to vary the distance between the sprocket shafts of the belt to take up slack which may occur therein the member 21 is provided at one end 5 with bifurcated portions 22 between which is slidably mounted a split bushing 23 having portions 24 overlapping the adjacent sides of the bifurcated portions. To prevent the bushing and consequently the adjacent 10 end of member 21 from moving longitudinally on the shaft 7, the latter may advantageously be integrally formed with circumferential lugs 25 between which the bushing is disposed. A set screw 26 may be conveniently employed for preventing relative 15 movement between the member 21 and the bushing 24. At its opposite end the member 21 is formed with an aperture into which a bushing 27 of suitable wear resisting metal 20 may be driven. The shaft 8 which extends through the bushing 27 is preferably provided with two sleeves 28 to prevent the adjacent end of the member 21 from shifting longitudinally of the sprocket shaft.

The actuating bar 19 is of channel shape and is designed to straddle the member 21 to which it is secured by bolts 29 which pass through its legs 30. Extending upwardly 25 from the web 31 of the member 19 is a portion 32 of a width substantially equal to the thickness of the anti-friction rollers 33 with which all of the brackets 17 of the stripping devices are preferably provided. Disposed 30 on one side of the bar 19 is the member 18 and it is secured to the latter and to the member 21 by two of the bolts 29 heretofore referred to. On the opposite side of the bar 19 is the actuating bar 20 which is secured at one end to the bar 19 and member 21 by another of the bolts 29 and at the other end by bolts 34 to the member 21.

In the operation of the machine the tobacco leaves may be fed to the stemming mechanism by any suitable means such as endless 50 chains 35 as fully illustrated and described in my pending application, Serial No. 376,915 to which reference has heretofore been made. The tobacco leaves are gripped firmly between the endless chains so that they cannot move in the direction of travel of the stripping devices but the mechanism is so arranged that the chains feed the leaves continuously rather than intermittently. Referring to Figure 1 it will be seen that one set 55 of the stripping devices has practically completed its stripping operation while another set is just beginning its operation. In this Figure it will be seen that the stripping devices C¹ and C² have moved into inoperative positions since they have passed beyond their

respective actuating bars 18 and 19 while the device designated C³ is still in operative position as the roller 33 with which the pivoted member 11 is provided is in engagement with its actuating bar. The stripping device A¹ 70 of the next set of strippers has already been moved into operative position by its roller engaging the bar 18 while the devices A² and A³ still remain in inoperative position. The relation of parts shown in this figure are reproduced in Figure 16 which is a plan view of the lower belt. To clearly show the manner in which the stripping devices cooperate with the tobacco leaves the latter have been 75 illustrated diagrammatically.

As the belts continue their movements the stripping devices C³ will move into inoperative positions as soon as their rollers have moved out of engagement with the actuating bars 20. At about the time this occurs the stripping devices A¹ will have moved into a position such that they are ready to be free of their operating bars 18 and the stripping devices A² will be in position to engage their operating bars 19 and thereby move into operative position as the devices A¹ move into inoperative position. This relationship of parts is depicted in Figure 17. As the belts continue to move the devices A² will assume a position such that they will be free of their operating bars 19 while the devices A³ will be in position to engage their operating bars 20 whereby the devices A³ are moved to operative position at about the time or somewhat before the devices A² move into operative positions. This relationship of parts is depicted in Figure 18.

From the foregoing it will thus be seen that the devices of each set are successively actuated whereby each device strips only a portion of the lamina from the stem but yet they cooperate with each other in such manner that all of the lamina is efficiently and quickly stripped from the stem. Although each of the stripping devices is shown as being provided with a spring 36 for insuring its return into an inoperative position after moving from engagement with its actuating bar this spring may or may not be used since the depending members 17 are so arranged as to constitute counterbalancing means for insuring movement of the devices into inoperative position. In other words the depending members 17 are so associated with the pivoted members 11 of the stripping devices that when they move out of engagement with their actuating bars the members 11 will automatically move into inoperative positions. Of course, this would only be true with the devices on the lower belt as the pivoted members of the devices on the upper belt will remain in what amounts to operative positions but as corresponding members of both belts must cooperate, as shown in Figure 2, to strip the lamina from the stem they are, in 133

fact, inoperative to strip the tobacco leaf. The devices on the upper belt will, however, assume inoperative positions as soon as they are brought around on the upper section of 5 the belt and likewise the devices on the lower belt will assume what would ordinarily be operative positions when they are disposed on the lower section of that belt. However, the relative positions of the stripping devices when on the upper and lower sections 10 of the upper and lower belts, respectively, is of no import as is pointed out above it is necessary, in the present embodiment of the invention, that corresponding devices of the 15 two belts cooperate with each other in order to strip the lamina from the stem of the leaf and this cooperation is only brought about by the depending brackets 17 of the various stripping devices engaging their respective 20 actuating bars.

The last or third device of each set of strippers on the upper belt is provided with means for cutting or severing the stem of the leaf adjacent its tip end. In the present 25 embodiment of the invention this means comprises a slidable member 37. This cutter member is disposed between the stripping plate 14 and a wall 38 formed integrally with the pivoted member 11 and comprises a plate 39 having a serrated edge similar to that of the stripper plate and a bar or rod 40 projecting beyond the side edges of the plate. The cutter member is slidably associated with the 30 stripping device by means of screws 41 which extend through elongated slots 42 formed in the cutter member and connect the spaced walls of the pivoted member 11. If desired, ferrules 43 may be mounted upon the screws to maintain the spaced walls in the required 35 spaced relation to permit of free sliding of the cutter member.

Disposed on each side of the upper belt in the path of travel of the end portions of the bar 40 of the cutter member is means for actuating or moving the cutter plate relatively 40 to the stripping plate for severing the stem. This means comprises two angularly shaped members 44 and 45, respectively, each of 45 which is provided with an inwardly projecting portion adapted to engage the adjacent end of the rod 40. The inwardly projecting portion with which the angle member 44 is provided is in the form of a channeled or 50 grooved member 46 which may be adjustably secured to the angle member by a set screw 47. The inner face of the member 46 is bevelled as at 48 so that as the adjacent end of the bar 40 comes into engagement therewith the bar and cutter plate are moved transversely of 55 the associated stripping device. The inwardly projecting portion with which the angle member 45 is provided comprises an integral extension 49 having a bevelled surface 60 adapted to engage the adjacent end of the cutter bar 40 to return it to the position which 65

it occupied before being actuated by the member 46. By arranging the member 46 so that it may be secured to the angle member 44 in various positions of adjustment it will be perceived that the cutting apparatus may be operated so as to accommodate tobacco leaves of varying length.

The angle members 44 and 45 may be supported in any suitable manner as by means of brackets 51 rigidly connected to bars 52 mounted upon and secured to opposite sides of the member 21 by bolts 34 heretofore referred to. Furthermore, the outer ends of the bar 40 of the cutter member may, if desired, be formed or provided with anti-friction rollers 53.

From the foregoing it will be perceived that I have provided simple and rugged means for stripping the lamina of the leaf by a plurality of successive stripping operations and that simple means is also provided for cutting the stem of the leaf adjacent its tip end.

I claim:

1. A tobacco leaf stemming machine having an endless belt provided with a set of devices for stripping the lamina of the leaf from its stem, said devices being adapted to strip successive portions of the lamina from the stem.

2. A tobacco leaf stemming machine having an endless belt provided with means for stripping the lamina of the leaf from the stem, said means comprising a plurality of devices for successively cooperating with the lamina whereby each of said devices is adapted to strip a portion of the lamina from the stem.

3. A tobacco leaf stemming machine having an endless belt provided with a set of devices for stripping the lamina of the leaf from the stem, said devices being successively movable into inoperative position whereby each of them is adapted to strip a portion of the lamina from the stem.

4. A tobacco leaf stemming machine having an endless belt provided with a plurality of devices for stripping the lamina of the leaf from the stem, said devices being movable into and out of operative positions whereby they are adapted to strip successive portions of the lamina from the stem.

5. A tobacco leaf stemming machine having an endless belt provided with a plurality of devices for stripping the lamina of the leaf from the stem, each of said devices having a portion movable into and out of stripping cooperation with the leaf whereby said devices are adapted to strip successive portions of the lamina from the stem.

6. A tobacco leaf stemming machine having an endless belt provided with a plurality of devices for stripping the lamina of the leaf from the stem, each of said devices comprising a pivotally mounted serrated plate, and

- means for actuating said plates whereby the latter are adapted to successively cooperate with the leaf for stripping the lamina from the stem.
- 5 7. A tobacco leaf stemming machine having an endless belt provided with a set of devices movable longitudinally of the leaf for stripping the lamina thereof from the stem, each of said devices involving a member movable into and out of cooperation with the leaf for stripping only a portion of the lamina from the stem.
- 10 8. A tobacco leaf stemming machine having an endless belt provided with a set of devices for stripping the lamina of the leaf from its stem, said devices being arranged in tandem relation and each comprising a pivotally mounted stripping member, and means cooperable with the stripping members for successively rendering them inoperative whereby each is adapted to strip a portion of the lamina from its stem.
- 15 9. A tobacco leaf stemming machine having an endless belt provided with a set of devices for stripping the lamina of the leaf from its stem, said devices being arranged in tandem relation and each comprising a pivotally mounted stripping member provided with a projecting portion, and means disposed in the path of travel of the said projecting portions for cooperating therewith whereby the stripping members are successively rendered inoperative so that each of them is adapted to strip a portion of the lamina from its stem.
- 20 10. A tobacco leaf stemming machine having an endless belt provided with a set of devices for stripping the lamina of the leaf from its stem, said devices being arranged in tandem relation on the outer side of said belt and each comprising a pivotally mounted stripping member, each of said members having a portion projecting on the opposite side of the belt, and means disposed in the path of travel of said projecting portions for cooperating therewith to render said stripping members inoperative whereby each of them is adapted to strip a portion of the lamina from its stem.
- 25 11. A tobacco leaf stemming machine comprising a pair of endless belts arranged in superposed relation, each of said belts being provided with a plurality of devices respectively cooperable with the corresponding devices of the other belt for stripping the lamina of the leaf from the stem, the cooperating devices of each belt being successively movable into inoperative position whereby each of them is adapted to strip a portion of the lamina from the stem.
- 30 12. A tobacco leaf stemming machine comprising a pair of endless belts arranged in superposed relation, each of said belts being provided with a plurality of devices respectively cooperable with the corresponding devices of the other belt for stripping the lamina of the leaf from the stem, each of said devices comprising a pivotally mounted stripping member, the members of the devices on one of said belts being successively movable into inoperative position whereby each of said members is adapted to strip a portion of the lamina from its stem.
- 35 13. A tobacco leaf stemming machine comprising a pair of endless belts arranged in superposed relation, each of said belts being provided with a set of devices, the devices of each set being arranged in tandem and those of one set being respectively cooperable with the corresponding ones of the other set for stripping the lamina of the leaf from the stem, the cooperating devices of each set being successively movable into inoperative position whereby each of said cooperating devices is adapted to strip a portion of the lamina from its stem.
- 40 14. A tobacco leaf stemming machine having an endless belt provided with a plurality of sets of stripping devices, each of said sets being cooperable with a different leaf for stripping the lamina thereof from its stem and the devices of each set being successively operable to strip only a portion of the lamina of the leaf from its stem.
- 45 15. A tobacco leaf stemming machine having an endless belt provided with a plurality of sets of devices for stripping the laminae of leaves from their stems, each of said sets being operable upon leaves different from those operated on by the other sets and the devices of each set being adapted to strip successive portions of the lamina of the cooperating leaf from its stem.
- 50 16. A tobacco leaf stemming machine having an endless belt provided with a device for stripping the lamina of the leaf from the stem, said device involving means for cutting the stem of the leaf adjacent its tip end.
- 55 17. A tobacco leaf stemming machine having an endless belt provided with a device for stripping the lamina of the leaf from its stem, said device comprising a serrated plate, and means movable relatively to the latter for cutting the stem of the leaf adjacent its tip end.
- 60 18. A tobacco leaf stemming machine having an endless belt provided with a device for stripping the lamina of the leaf from its stem, said device comprising two relatively movable members, and means for actuating one of said members to cut the stem of the leaf adjacent its tip end.
- 65 19. A tobacco leaf stemming machine having an endless belt provided with a device for stripping the lamina of the leaf from its stem, said device comprising two relatively movable members, one of said members being fashioned with a lateral projection, and means engageable with said projection for

actuating the said member to cut the stem of the leaf adjacent its tip end.

20. A tobacco leaf stemming machine having an endless belt provided with a device for stripping the lamina of the leaf from its stem, said device being provided with a relatively movable member having an extension, and adjustable means disposed in the path of travel of said extension for displacing the latter to cut the stem of the leaf adjacent its tip end.

21. A tobacco leaf stemming machine having an endless belt provided with a set of devices for stripping the lamina of the leaf from its stem, said devices being arranged in tandem and adapted to successively cooperate with the leaf whereby each of them is adapted to strip a portion of the lamina from its stem, the stripping device last to cooperate with the leaf being provided with means for cutting the stem thereof adjacent its tip end.

22. A tobacco leaf stemming machine comprising an endless revolvable carrier provided with a set of devices for stripping the lamina of the leaf from its stem, said devices being constructed and arranged to strip successive lengthwise portions of the lamina from the stem.

In testimony whereof I affix my signature.
ROBERT L. WEISNER.
